United States Patent Office

Des. 186,804
Patented Dec. 1, 1959

186,804

DISPLAY STAND

Christopher L. Migliaccio, Warwick, R.I., assignor to Ritz Metal Products Co., Providence, R.I., a corporation of Rhode Island

Application March 20, 1959, Serial No. 55,097

Term of patent 3½ years

(Cl. D80—9)

FIG. 1

FIG. 4

Fig. 1 is a front elevational view, in an upright folded position, of a display stand embodying my new design;

Fig. 2 is a side elevational view thereof in an open position;

Fig. 3 is a rear elevational view of the stand shown in Fig. 2; and

Fig. 4 is a top plan view of the stand as shown in Fig. 1.

I claim:

The ornamental design for a display stand, as shown.
